D. G. GALBRAITH

TIE FASTENER

Filed Sept. 19, 1919

David G. Galbraith

Inventor

UNITED STATES PATENT OFFICE.

DAVID G. GALBRAITH, OF MINERAL WELLS, TEXAS.

TIE FASTENER.

Application filed September 19, 1919. Serial No. 324,822.

To all whom it may concern:

Be it known that I, DAVID G. GALBRAITH, a citizen of the United States, residing at Mineral Wells, in the county of Palo Pinto 5 and State of Texas, have invented a new and useful Tie Fastener.

This invention relates to a tie fastener of the class adapted to be used for general purposes; and has for its object to provide 10 a device of this character that embodies certain novel features in the construction, arrangement and operation of the same as will be hereinafter set forth.

This device is composed of two separable 15 parts, comprising an angular clamp consisting of a single piece of spring wire bent into the desired form. The second part of the device is a tying cord used in connection with the clamp part and so interlaced 20 therewith as to prevent accidental separation and dispenses with the necessity of tying and untying knots in practical working.

The single figure shown in the drawing 25 is a plan of a device embodying the improvement.

The wire clamp-part, comprises a short pinch bend 1, a short bend 2 extending inwardly therefrom, a bend forming a body portion 3 which is a continuation thereof, 30 elongated pinch slot 4, which combines the different binding cord angles in the operation of drawing the same tight in its binding relation.

The tying cord passes through different 35 angles of the clamp-part and around both ends and the respective sides of the package in the complete operation. Place the clamp

on the package under the thumb, having first secured the end of the cord in the elongated slot part 4, then down under, up over and 40 back over and passing the cord through short bend 2, then back through bend 3 and then under the package and over the tying side where the cord is tightly drawn in through pinch slot 1 and drawn tightly 45 therein with a binding clamp action which securely holds the cord in place. The cord is easily released by drawing the same back through snap slot 1, by an outward releasing movement. 50

The slight inward depression 5 slightly narrows the passage and prevents the cord from a tendency to slip out. The terminal spring end 6 extends a little past the adjacent end 1 and provides for a yielding 55 closure.

This arrangement presents a device that may be manipulated with facility; will not untie or loosen up or become tangled with other packages when transported in bulk. 60

What I claim is—

1. A tie fastener, consisting of a wire bent in a single curve intermediate its length to provide two arms extending laterally with respect to each other, one of said arms being longer than the other and each of said arms being formed with a return bend providing respectively a long and short pinch slot. 65

2. The structure specified in claim 1, and 70 having the returned free ends of said bends substantially contacting each other at an acute angle.

DAVID G. GALBRAITH.
